(57) **CLAIM**

The ornamental design for a headshell, as shown and described.

DESCRIPTION

FIG. 1 is a front view of a headshell;

FIG. 2 is a rear view thereof;

FIG. 3 is a left side view thereof;

FIG. 4 is a right side view thereof;

FIG. 5 is a top plan view thereof; and,

FIG. 6 is a bottom plan view thereof; showing our design. The present article is a headshell which is an adapter for attaching a cartridge of a record player to a tonearm. The design shown is not to be limited to any particular size and may be scaled larger or smaller.
